UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

VALVE FOR ROCK DRILLS.

Original application filed, October 16, 1922, Serial No. 594,728. Divided and this application filed January 15, 1925, Serial No. 2,553.

To all whom it may concern:

Be it known that I, LEWIS C. BAYLES, a citizen of the United States, and a resident of Easton, county of Northampton, State of Pennsylvania, have invented a certain Valve for Rock Drills, of which the following is a specification, accompanied by drawings.

This application is a division of my co-pending U. S. application, Serial No. 594,728, filed October 16, 1922.

This invention relates to rock drills, but more particularly to a differential spool type valve having a plurality of heads for effecting the distribution of motive fluid to the cylinder of the rock drill. In the present valve, there are actuating faces on the valve heads, but two of the heads are larger than the remaining head, and these enlarged heads are provided with opposed holding faces. It has been found that by forming separate actuating and holding faces on the heads of the valve a high drilling efficiency will be attained, and that the valve will be quick and positive in its action.

Other objects will hereinafter appear in the following description and the accompanying drawings illustrating the invention in its preferred forms.

Figure 1 is a diagrammatic longitudinal sectional elevation of a part of a rock drill embodying the invention.

Figure 2 is a diagrammatic longitudinal sectional elevation of a part of a rock drill showing a modified form of the valve.

Figure 3 is a diagrammatic longitudinal sectional elevation of a part of a rock drill showing a modified form of valve with the reciprocating parts in one position, and

Figure 4 is a view similar to Figure 3 showing the reciprocating parts in another position.

Referring to the drawings, a portion of a fluid actuated rock drill is shown having a cylinder A and a valve chest B. A piston C, having a reduced cylindrical extension, is arranged within the cylinder to reciprocate therein and deliver impact blows upon a drill steel. The rearward end of

the cylinder is sealed by a back head D, and a front cylinder washer E serves as a closure for the forward end of the cylinder and has a hollow bore to receive the reduced extension of the piston C.

A valve chamber F, having a reduced bore at one end, is formed in the valve chest and is in communication with a source of motive fluid (not shown) through a central inlet port H, and is provided with main exhaust ports J and K between the inlet port H and the ends of the valve chamber F. Distribution of the motive fluid to the cylinder A and the exhaust of motive fluid therefrom is controlled by a valve L having a central head O to control the inlet port H. A face P of the head O is used as a holding face against which the pressure of the motive fluid acts to hold the valve L in its thrown position during the admission of motive fluid to the forward end of the cylinder A. The valve L also has a head Q of the same diameter as the head O to control the exhaust port J, and a head R of smaller diameter to control the exhaust port K.

Disposed in one end of the valve chamber F is a plug S to seal the chamber. The plug S is preferably provided with an extension having a face T which projects into the recess of the head R and serves as a stop for the valve. The other end of the chamber F is sealed by a plug U having a reduced cylindrical extension which cooperates with the head Q of the valve to form a holding pressure chamber V, and an actuating pressure chamber W, and is also provided with a face X to serve as a stop at the other end of the chamber for the valve L.

Supply passages Y and Y' connect the valve chamber with the forward and rearward ends respectively of the cylinder, and passages Z and Z' effect communication between the chambers in which actuating faces b and f of the valve heads Q and R respectively are located and points in the cylinder between the passages Y and Y'.

In operating the drill, let it be assumed

that the reciprocating parts are in the positions indicated in Figure 1 of the drawings, so that motive fluid entering the valve chamber F will pass through the supply passage Y to the front end of the cylinder A and impel the piston C toward the rearward end of the cylinder. Since the diameter of the head O of the valve L is greater than that of the head R, the valve will remain in its thrown position until the passage Z is uncovered by the piston C, at the same time fluid will pass through said passage into the chamber W, and acting against the actuating face b of the head Q will throw the valve against the face T of the plug S, thereby uncovering the exhaust port K and permitting the motive fluid in the forward end of the cylinder to escape to atmosphere while live motive fluid is admitted to the rearward end of the cylinder A through the supply passage Y'.

At the same time motive fluid will flow through a passage c in the valve head Q, and acting against a holding face d formed on the same side of the head Q as the actuating face b will hold the valve in its thrown position until the piston C uncovers the passage Z', thereby permitting live motive fluid to enter the chamber e, and acting against the actuating face f of the head R will overcome the pressure of the motive fluid within the holding chamber V and throw the valve to the position indicated in the drawings. Simultaneously the motive fluid in the rearward end of the cylinder will escape through the supply passage Y', and though the exhaust port J to atmosphere, and the forward end of the cylinder is again subject to live motive fluid, thus completing the cycle of operations.

In Figure 2 a modified form of a differential spool valve is shown, having separate actuating and holding faces. In this instance, the valve L' is provided at one end with a reduced cylindrical extension q having a holding face h. This extension is adapted to reciprocate within the bore j of the plug k, said bore serving as a pressure chamber, which is in communication with the rearward end of the cylinder. A face o of the valve head Q' is utilized as an actuating face against which live motive fluid will act to overcome the pressure against the face P of the central head O to throw the valve to the other limiting position.

The valve L' is preferably made as light in weight as possible without sacrificing strength. To this end the middle head O and one outer head Q' are recessed on the sides and a central bore p is formed part way through the center of the valve. In this instance, the admission and exhaust of motive fluid, and the distribution thereof are effected in the same manner as in Figure 1, while the ports and passages for re-

ciprocating the piston C and the valve L' are also like those described in connection with Figure 1.

In the modification illustrated in Figures 3 and 4, a differential spool type valve L', having separate actuating and holding faces, is shown in the valve chamber F'. The central head O' and the head Q' are of the same diameter with relation to each other, and embody the characteristics of the corresponding heads described in Figure 1. In this instance the smaller valve head R' is formed solid and is provided with an unbroken actuating face f'. The admission and exhaust of motive fluid, and the distribution thereof, are effected in the same manner as described in connection with Figure 1.

I claim:

1. In a rock drill, the combination of a cylinder, a piston within the cylinder, a valve chest having a valve chamber and an inlet port communicating with the valve chamber, exhaust ports connecting the valve chamber with the atmosphere, and a valve within the chamber to control the ports, said valve having a central head with a holding face, an end head of the same diameter with separate holding and actuating faces and another end head of smaller diameter with an actuating face to enable pressure fluid acting against the last said actuating face to overcome pressure fluid acting against the holding face of the other end head. 100

2. In a rock drill, the combination of a cylinder, a piston within the cylinder, a valve chest having a valve chamber and an inlet port communicating with the valve chamber, exhaust ports connecting the valve chamber with the atmosphere, a valve within the chamber to control the ports, said valve having a central head with a holding face, an end head of smaller diameter with an actuating face against which pressure fluid may act for throwing the valve against pressure acting in the opposite direction and another end head with separate actuating and holding faces for returning the valve and holding said valve, and means for sealing the ends of the chambers, one of said sealing means cooperating with one end of the valve for forming separate actuating and holding pressure chambers. 110

3. In a rock drill, the combination of a cylinder, a piston within the cylinder, a valve chest having a valve chamber, an inlet port communicating with the valve chamber, and exhaust ports connecting the valve chamber with the atmosphere, a valve within the chamber to control the ports, said valve having a central head with a holding face, an end head of smaller diameter with an actuating face to enable said valve to be thrown against pressure acting against the opposite end of the valve and another 120

end head with separate actuating and holding faces for throwing the valve and holding said valve in thrown position, and plugs to seal the ends of the chambers, 5 one of said plugs cooperating with one end of the valve for forming separate actuating and holding pressure chambers, said valve chest being provided with ports and passages for admitting motive fluid to the cylinder and exhausting it therefrom and for 10 actuating and holding the valve.

In testimony whereof I have signed this specification.

LEWIS C. BAYLES.
